UNITED STATES PATENT OFFICE.

OTTO CZARAN, OF LONG ISLAND CITY, NEW YORK.

APPARATUS FOR MAKING BELTING.

Application filed January 28, 1919. Serial No. 273,643.

To all whom it may concern:

Be it known that OTTO CZARAN, subject of Austria Hungary, and resident of Long Island City, in the county of Queens and State of New York, has invented certain new and useful Improvements in an Apparatus for Making Belting, of which the following is a specification.

The present invention relates to belting and particularly to the making of light belting such as is used for driving sewing machines and such other light machinery.

The object of my invention is to provide apparatus for making such belting from a side of leather, the apparatus being so arranged and embodying such means as to continuously feed the material in at the fore end of the machine and pay the same out at the rear end in the form of finished belting of desired cross-section, smoothed, hardened and polished.

My invention embodies means for cutting the leather strip into a predetermined width to form a strip square in cross-section, means for shaping this into a belt of circular or other desired cross-section, means for stretching the belt when finished from stretching unduly under strain; means for smoothing, hardening and polishing said belt, and means for winding the finished belt on a spool removable from the machine and from which it may be paid out in desired lengths.

Referring to the drawings which form a part of this specification,

Fig. 1 is a plan view of a machine embodying my invention and showing a table upon which are mounted the specific devices for performing the several operations required in making the round belt and preferred means for driving said mechanism.

Fig. 2 is a side elevation of the structure illustrated in Fig. 1 and partly in longitudinal section.

Fig. 3 is a longitudinal view partly in section illustrating a construction for holding the disc of leather while it is rotated between a pair of rollers prior to being cut by the dividing knife and referred to in Fig. 1 by line 3-3.

Fig. 4 is a cross-sectional view of the offset line 4-4 of Fig. 2.

Fig. 5 is a cross-sectional view on line

5-5 of Fig. 2 disclosing the removable spool in longitudinal section.

Fig. 6 is a detailed vertical sectional view on line 6-6 of Fig. 1 showing the means whereby the roller which is held to permit of lateral adjustment to provide for cutting the belt to a desired width.

Referring in detail to the drawing, A indicates a table made preferably of cast iron upon which are mounted rollers A', A', A', upon which is placed a disc of leather from which the belt is to be formed. B and B' indicate two rolls, the lower one B, of which is driven from the countershaft C through the miter gearing C' and the edge of the leather disc is held between the said rolls and propelled thereby against the knife D which cuts it to the proper width, said width being determined by the position of the rolls D', D'—as will hereinafter more fully appear. The upper roll B' is held in a frame B² which in turn is journaled on the pins B³, B³ which have their bearings in the outer frame B⁴ which in turn is held on one end of the lever B⁵ and is pressed toward the roll B by the spring B⁶ as will be readily understood. This construction permits the leather disc to be firmly held and propelled by the roller B and is made to conform to the variations in the thickness of the leather and in case the leather is uneven or warped, to force the same into sure contact. After the strip has been cut by the knife D it passes between two pairs of guide rolls, E, E, disposed in planes transverse to each other, to the cutting knife or trimmer F consisting of a conically formed tube, the small periphery of which is sharpened to provide a circular cutting edge to round the square belt strip into circular cross-section. The top rolls of the rolls E, E are also provided with a spring E' for tensioning them against the lower rolls. The belt then passes between the grooved rollers G, G, which are held closely together by a spring G' located in the housing G² and is then led between the rollers H, H, which are submerged in an oil bath I and thence between the rollers J, J, and K, K, and into the spool L on which it is wound in successive layers and may be removed at this point if desired. Ordinarily, however, the spool L serves to pull the belt

through, the latter being wound several turns thereon and being driven through the shaft C and gearing C² the belt is drawn through by the spool L as it is being cut and shaped. The belt is then carried over the spool M and between the rollers m, m, to the friction wheels, N, N, and polishing wheels N⁴, N⁴, respectively. The contact surfaces are the polishing wheels are covered with raw hide or other suitable material to polish the surface of the round belt by friction. The friction wheels N, N, are driven at a high speed and serve to smooth and harden the surface of the belting. These sets of friction and polishing wheels are driven from the shaft O through the gearing O', and the first set of polishing rolls is driven by means of the belt P and gearing P'. The wheels N, N, are mounted on shafts N², N² respectively, supported in standards N³, N³ and the polishing wheels N⁴, N⁴ are held in a housing N'. The belt then is passed successively between the rollers R, R, S, S, T, T, and U, U, and on to the spool driven through the miter gearing W' which is driven from the shaft O as will be clear from the drawing. Clutch means X, X' are provided to connect and disconnect shafts C and O respectively from the main driving shaft Y.

The knife D is held in a bracket D² which bracket also supports one of the rollers E, and said roller E and knife D are therefore adjustable with the bracket and held in adjusted relation by the screws D³ passing through the slot D⁴ formed in the bracket.

The rollers D', D' and the roller E held by the bracket E' are adjustable to and from the strip of leather which is to be formed and the adjusting means consist of a plurality of wedge members d which clamp the end of the journal d' firmly in any desired lateral adjustment.

Mounted on the table A is a bracket a which is adjustable longitudinally of the table by reason of the slots a' and held in adjusted position by bolts b, b, e, indicates a drum having a continuous cam groove e' formed therein. Mounted on the bracket a is an arm f one end of which is pivoted on the bracket as at g while the other end carries the guide pulleys K, K which are made to swing in the arc of a circle by the travel of the arm f in the groove e' by means of a stud i secured to the arm f and free to slide in the slot f' formed in the arm f. The drum in turn is driven from the worm gear k which by reason of its slow transmission moves the drum slowly and in turn causes the pulley k to be swung back and forth to wind the belt on the spool L in successive layers, if desired. Ordinarily, however, the stud i is removed and the belt permitted after having a few turns taken on the spool 65 to continue on to the spool M and thence to

the polishing rolls. By a longitudinal adjustment of the bracket a the arc through which the pulley K, K swings may be varied within limits to accommodate belts of different diameter to be carried back and forth the entire length of the spool. For large variations the gearing may be changed as will be readily understood. When winding the belt after polishing on the removable spool L a similar drum n and like cam mechanism as just described is employed. The guide rolls H, H are carried on the lower end of a rod H' which is supported in the arm f and which is free to slide in a guide formed in the casting H² secured on the underside of the arm f and the belt can be placed under any required tension by means of the lever H³ and held in the adjusted position by means of the bracket H⁴ also carried by the arm f. As the arm f swings back and forth the rolls H, H also swing back and forth through the bath. The rolls J, J are slidably mounted on shafts extending across the bed A to the width substantially of the bath to permit the belt to remain in alignment when leaving the rolls H, H and passing to the rolls K, K. I preferably use a bath of oil but may use any other suitable fluid.

The detailed construction of the removable spool is illustrated in Fig. 5, in which L represents the spool and h, h indicate flanges which carry pins h', h' to engage corresponding openings in the flanges of the spool. A bolt h² extends through an opening h³ formed in one of said flanges and screws into the tapped socket h⁴ of the opposite flange. So that, by removing said bolt h² and sliding, the right hand flange h can be moved in the bearing h⁵ a distance corresponding to the length of twice the length of the pins h', thus freeing the spool as will be readily understood.

A brake is provided to prevent the reel M from unwinding except as the belt is drawn to the polishing rolls. In the form shown this consists of a belt r, one end of which is held to a post s and the other end of which carries a weight t, the friction of the belt preventing the reel from unwinding except as the belt is withdrawn therefrom.

Having thus described my invention, I claim:

1. A belt making machine comprising a table, means for holding a sheet of belting material thereon, a knife adapted to cut a strip from said sheet, a trimmer adapted to form said strip into one of desired cross-section, means for guiding said strip to said trimmer, a bath, means for opposing said drawing means to produce a predetermined tension in the strip, and a reel for holding said belt.

2. A belt making machine comprising a table, means for holding a sheet of belting

- material thereon, a knife adapted to cut a strip from said sheet, a trimmer adapted to form said strip into one of desired cross-section, means for guiding said strip to said trimmer, a bath, means for drawing the strip through said bath under a predetermined tension, friction wheels for smoothing and hardening the belt, polishing wheels, and means for drawing said strip between said wheels to finish the same. 3. In a machine for making belting from a sheet of belting material in combination with a stripping knife adapted to cut a strip of predetermined width from said sheet and a trimmer to form said strip into one of desired cross-section, a feed device for feeding material of said sheet to said knife, and said trimmer, comprising a frame, and a pair of rollers, disposed oppositely to each other, one of said rollers being pivotally held in said frame in such manner that the feed device adjusts itself automatically to varying thickness and unevenness of said belting material. 4. In a machine for making belting from a sheet of belting material, in combination with a stripping knife adapted to cut a strip of predetermined width from said sheet and a trimmer to form said strip into one of desired cross-section, a feed device for feeding material of said sheet to said knife and said trimmer comprising a frame, and a pair of rollers disposed oppositely to each other, one of said rollers being pivotally held in said frame, in such manner that the feed device adjusts itself automatically to unevenness of said belting material, and yielding means for forcing said pivoted roller towards its oppositely disposed roller. 5. A belt making machine for forming belting from a sheet of belting material comprising a stripping knife adapted to cut a strip of predetermined width from said sheet, a trimmer adapted to form said strip into one of desired cross-section, means for drawing said strip through the machine under tension, a reel and means for guiding said strip on to said reel in successive layers, said means comprising a drum having an endless cam groove formed therein, and means operating in said groove adapted to swing the strip to and fro across the length of said reel. 6. A belt making machine comprising a table, means for holding a sheet of belting material thereon, a stripping knife adapted to cut a strip of predetermined width from said sheet, a trimmer adapted to form said strip into one of desired cross-section, means for guiding said strip to said trimmer, a bath, means for drawing the strip through the bath, means for opposing said drawing, means to produce a predetermined tension in the strip. 7. A belt making machine comprising a table, means for holding a sheet of belting material thereon, a stripping knife adapted to cut a strip of predetermined width from said sheet, a trimmer adapted to form said strip into one of desired cross-section, means for guiding said strip to said trimmer, a bath, a pair of pulleys located in said bath between which said strip is drawn and means for subjecting said strip to a predetermined tension while passing through said bath. 8. A belt making machine comprising a table, means for holding a sheet of belting material thereon, a stripping knife adapted to cut a strip of predetermined width from said sheet, a trimmer adapted to form said strip into one of desired cross-section, means for guiding said strip to said trimmer, a bath, a pair of pulleys located in said bath between which said strip is drawn and means for subjecting said strip to a predetermined tension while passing through said bath, a reel for drawing said strip through said bath under tension, guiding means for guiding said strip upon said reel, said guiding means comprising an arm adapted to swing across the length of said reel, and a pair of guide pulleys suspended from the free end of said arm. 9. A belt making machine comprising a table, means for holding a sheet of belting material thereon, a stripping knife adapted to cut a strip of predetermined width from said sheet, a trimmer adapted to form said strip into one of desired cross-section, means for guiding said strip to said trimmer, a bath, a pair of pulleys located in said bath between which said strip is drawn and means for subjecting said strip to a predetermined tension while passing through said bath, said means comprising a rod from which said pulleys are suspended and means connected to said rod for forcing the same down to cause one of the pulleys to bear against the strip. 10. A belt making machine comprising a table, means for holding a sheet of belting material thereon, a stripping knife adapted to cut a strip of predetermined width from said sheet, a trimmer adapted to form said strip into one of desired cross-section, means for guiding said strip to said trimmer, a bath, a pair of pulleys located in said bath between which said strip is drawn, means for opposing said drawing means to produce a predetermined tension in the strip, a reel for said strip, guiding means for guiding said strip upon said reel, said guiding means comprising an arm adapted to swing across the length of said reel, and means for adjusting the arc through which said arm swings. 11. In a machine for making belting from a sheet of belting material, a stripping knife adapted to cut a strip of predetermined width from said sheet, a trimmer adapted to

4
form said strip into one of desired cross-section, means for guiding said strip to said trimmer, means for drawing said strip under tension through the machine, a removable reel on which said strip is wound, friction wheels for smoothing and hardening the belt, polishing wheels therefor, a main driving shaft, an auxiliary shaft for said smoothing and polishing wheels and clutch means

for driving said auxiliary shaft from said main shaft.

Signed at New York city in the county of New York and State of New York this 17th day of January A. D. 1919.

OTTO CZARAN.
